UNITED STATES PATENT OFFICE.

HIRAM STEVENS MAXIM, OF LONDON, ENGLAND.

AUTOMATIC GUN.

SPECIFICATION forming part of Letters Patent No. 447,525, dated March 3, 1891.

Application filed June 10, 1890. Serial No. 354,931. (No model.) Patented in England June 1, 1886, No. 7,354; in France June 30, 1887, No. 181,516; in Belgium October 15, 1887, No. 79,005; in Italy November 26, 1887, No. 22,500; in Germany January 20, 1888, No. 41,870, and in Austria-Hungary April 21, 1888, No. 34,166.

To all whom it may concern:

Be it known that I, HIRAM S. MAXIM, mechanical engineer, a citizen of the United States, residing at London, England, have invented certain new and useful Improvements in Automatic Guns, of which the following is a specification, reference being had to the accompanying drawings.

This invention I have shown and described in the following patents: English Patent No. 7,354, dated June 1, 1886; France, No. 181,516, dated June 30, 1887; Belgium, No. 79,005, dated October 15, 1887; Germany, No. 41,870, dated January 20, 1888; Austria-Hungary, No. 34,166, dated April 21, 1888, and Italy, No. 22,500, dated November 26, 1887.

This invention relates to that class of guns invented by me and known as "automatic" guns, in which the operations of ejecting an exploded shell, reloading, and, in fact, all the effects or changes included in the cycle of operation of the gun subsequent to a discharge of the same are performed automatically in one or another way by energy properly stored and applied resulting from such discharge.

In other patents I have shown a variety of ways or devices for utilizing the recoil or the force of the discharge of a given gun for automatically effecting the operation, reloading, and firing, but in all cases the recoil or force of an explosion has been employed not only to reload the barrel in which such discharge has taken place, but also to produce the next discharge in the same barrel, and this statement applies even to those forms of guns which I have shown, in which two or more barrels are associated and mounted in the same frame or support. My present invention, however, is an improvement in this respect. I have devised a multibarrel gun—that is to say, a gun composed of a plurality of barrels and breech mechanisms mounted on or in the same frame or support—in which the discharge of one barrel is dependent on and effected by the discharge of another in such manner that when one is started in operation or discharged all will be discharged successively so long as a supply of shells or cartridges is furnished to each. When two or more automatic guns are arranged in a

common frame or support and constructed so as to operate independently of one another, their discharge will not take place with uniform rapidity by reason of differences in the quality and quantity of the powder contained in the cartridges and various other causes. I therefore make the firing of one gun dependent upon the action of the breech mechanism of another gun—that is to say, I so construct a gun with two or more barrels that the release of the hammer for effecting the discharge of a cartridge in either of said barrels will be performed by force created by the explosion of a cartridge in another of the said barrels. For example, the force created by the explosion of a cartridge in the first barrel will release the hammer of the second barrel, the force created by the explosion in the second barrel will release the hammer in the third barrel, and so on, the force created by the explosion in the last barrel releasing the hammer of the first barrel. This principle of operation may be carried out in various ways, and I thus insure a constant or approximately constant and rapid fire.

In the accompanying drawings, in which my improvements are illustrated, Figure 1 is a plan, partly in horizontal section, of a gun embodying my invention. Fig. 2 is a vertical longitudinal section of the same. Fig. 3 is a horizontal section of a portion of the breech mechanism on an enlarged scale, and Fig. 4 is a longitudinal vertical section of the same.

Referring to the drawings, A is a strong metal frame, which is provided with trunnions A', and is designed to be supported upon a tripod or other suitable mounting or carriage.

B B are the barrels, which have formed thereon or firmly attached thereto metal frames B', and which are fitted to slide longitudinally to and fro with the said frames in or between suitable guides formed on or attached to the frame A.

C C are the breech-blocks, which are fitted to slide to and fro in the inner frames B'. Each barrel has its breech mechanism arranged to operate independently of that of any of the other barrels. In other words, there are five automatic guns arranged side by side

in a common frame or support and operating independently of each other. As these guns are similarly constructed, I will hereinafter describe one of them. The breech-block C has a bar or strut C' hinged or pivoted thereto, as at C². This bar or strut is formed with a shoulder or projection C³, which is adapted to engage with a shoulder B² on the inner frame B' when the breech is closed, and thus 10 lock or secure the breech-block in the said frame and support the said block against the force of the explosion of a cartridge in the barrel. The rear end of C⁴ of this pivoted bar is taper or wedge shaped and is hooked, 15 as shown. An arm or projection A² is formed or fixed on the rear end of the frame A, so that when the inner frame B' and parts carried thereby have nearly terminated their recoil the under side of the hook C⁴ of the bar 20 C' will strike the arm or projection A², and the said bar will thus be lifted out of engagement with the shoulder B² on the frame B'.

D is a spiral spring, which is arranged within a chamber A⁸, formed in the frame A. 25 A bar D', Fig. 2, is fitted to slide longitudinally to and fro between suitable guides above the chamber A⁸, and is provided with an arm D², which works in the slot A⁴ in the top of the said chamber. The bar D' is also provided with a shoulder or projection D³, with 30 which the breech-block C engages, so that the said bar is drawn back with the said block. The spring D is thus compressed by the breech-block in its backward movement, and then 35 reacts to effect the forward movement of the said block.

D⁴ is a bar which is fitted to slide between guides formed on the frame A, and is connected with the inner frame B', as shown in 40 Fig. 4. The said will therefore move to and fro with the said frame. The bar D⁴ extends through the frame A, and can be drawn back with the frame B' and barrel B by hand when necessary. The said bar is, moreover, provided with shoulders or projections D⁶ D⁷ for 45 the purpose hereinafter specified.

E is a spiral spring, which is arranged within a tube or chamber A⁵, attached to the under side of the frame A. This spring is connected at its forward end to the frame A by means of a hook E', and at its rear end to a plunger E², fitted to slide in the said tube or chamber A⁵. This plunger is connected with the inner frame B' by means of a rod E³, 55 coupled to the said plunger and provided with a hook E⁴, which engages with the said frame B'. When the said frame recoils, the spring E is extended. The said spring then reacts to effect or assist in effecting the return 60 movement of the said frame and parts carried thereby. To prevent or diminish the shock produced by the recoil of the said frame and parts carried thereby, I provide a spring E⁵, which in the latter part of such recoil will 65 be compressed between the plunger E² and the rear end of the chamber A⁵. This spring, moreover, by its reaction assists in effecting

the return movement of the barrel B and frame B', while the breech-block is held back, as hereinafter set forth, and thus effectually 70 insures the starting of the empty cartridge-shells from the barrel in the manner hereinafter described.

The rod E³ is provided with a hook E⁶, and may be disengaged from the frame B' and 75 coupled to the rear end of the chamber A⁵ to permit the drawing back of the said frame by hand.

F is a bent lever, which is pivoted at F' to the frame A, and is formed with a hook 80 adapted to engage with the hook C⁴ of the pivoted bar or strut C', for the purpose of holding back the breech-block during the forward or return movement of the barrel and inner frame. 85

In the to-and-fro movement of the frame B' the shoulders or projections D⁶ D⁷ on the sliding bar D⁴ act alternately upon the bent lever F to cause its engagement with and disengage it from the said pivoted bar C'. 90

G is the extractor, which is carried by and pivoted to the breech-block C. The extraction of the empty cartridge-shells is effected by the moving forward of the barrel and inner frame, while the breech-block is held 95 back by the hooked lever F—that is to say, the cartridge-shell is held stationary with the breech-block, while the barrel is moved forward, and thus drawn off the said shell. The empty shells fall through apertures provided 100 for the purpose in the frames A and B'. The extractor is so constructed and arranged that when the frame B' and parts carried thereby are in their rearmost position the enlargement G' of the said extractor will be in contact with the part A⁶ of the frame A, and the extractor will thereby be held firmly in engagement with the head or flange of a cartridge-shell while the said shell is being started from the barrel. The said extractor is reduced in thickness at G² to form a spring 105 which bears upon a shoulder at the rear end of the breech-block. The hooked end of the extractor can therefore be readily moved over the flange of a cartridge in the barrel, 110 and will then be held in engagement therewith by the said spring. 115

J is a vertical hopper, feeder, or magazine, which is arranged above the barrel B, with its rear end a short distance in front of the breech end of the barrel when the latter is in firing position. The lowermost cartridge in the said magazine rests upon the top of the barrel behind a projection B³ thereon. When the barrel recoils, the said cartridge is moved 120 backward by the said projection into a chamber A⁷ in the frame A. To the top of this chamber, within the same are secured springs A⁸, which press downward upon the cartridge thus introduced into the chamber. When 125 the barrel and inner frame have moved forward and the empty shell has been extracted, the said cartridge is forced down in front of the breech-block by the springs A⁸ and is 130

supported upon the frame B', so that the said block in its forward movement will push the said cartridge into the barrel.

In accordance with the assumed conditions 5 of my invention a number of guns of this description are mounted side by side in the frame A, and that the discharge of one may be made dependent upon the action of another the following devices are associated 10 and combined with the parts above set forth.

The barrel which is to be first fired is provided with three sears I I' I''. Each of the other barrels is provided with two sears I I'. Each barrel or gun has a firing-pin H passing 15 through its breech-block, a hammer H'', pivoted to the frame A, and a mainspring H³, which is attached in any convenient manner to the said frame.

The sears I, I', and I'', pivoted upon a pin 20 or rod I², fixed in the outer frame, are acted upon by springs I³, which tend to hold them in engagement with the bent H⁴ of the hammer H'' when the hammer is cocked. Each sear I extends downward, and is arranged to 25 be automatically disengaged from the hammer by means of a projection C⁵ on the corresponding breech-block at the termination of the forward movement of the said block. Each sear I' is a bent lever, one arm of which 30 extends beneath a trigger-rod I⁴, and which is operated as hereinafter set forth.

The hammer is cocked in the recoil of the inner frame B' by the aid of a projection C⁶ upon the breech-block. The said hammer is 35 formed with cams H⁶, one on each side thereof, so that before it can act upon the firing-pin H it must depress the pivoted bar C', and thus insure the engagement of the shoulder C³ thereof with the shoulder B² on the inner 40 frame, and when the said hammer has operated to fire the gun it will prevent the disengagement of the said pivoted bar from the inner frame until the hammer is again cocked. I thus insure the proper closing of the breech 45 before the gun is fired.

Each sear I is arranged to be disengaged through the instrumentality of a projection B²⁵ on the next succeeding barrel or on the inner frame B', formed on or attached to the 50 said barrel.

The trigger-rod I⁴ has fixed thereon a series of cams I⁸, which are arranged to act upon the sears I', respectively, as hereinafter described. Each cam I⁸ is provided with a tooth I⁹, and has arranged in combination therewith a pawl v, which is coupled to a lever v', pivoted at v² to the frame A, and which is acted upon by a spring v³, whereby it is caused to engage with the said tooth I⁹. For 55 the sake of clearness in the drawings some of the cams I⁸ are omitted, only two of the said cams being shown in Figs. 2 and 4.

Considering the mechanism attached to any one of the barrels, as above described, its operation is as follows—that is to say, the parts are shown in Fig. 2 in the positions which they occupy when the firing-pin has been

struck by the hammer and the projectile is about to move forward in the barrel. The explosion of the cartridge causes the recoil of 70 the barrel B and the inner frame B' and parts carried thereby.

In this recoil the projection B³ pushes the lowermost cartridge in the magazine backward into the chamber A⁷, the spring D is compressed, and the spring E is 75 extended, as above described, the hammer is cocked, and is held in its cocked position by the sears. The pivoted bar C' then comes in contact with the arm or projection A² on the frame A, and is thereby disengaged from the 80 shoulder B² of the frame B'. Moreover, the bar D⁴ is moved backward until its projection D⁷ strikes the lever F and causes the same to engage with the pivoted bar C' and hold back the breech-block. In the latter portion of the 85 backward movement of the frame B' and parts carried thereby the spring E⁵ is compressed. By the reaction of the springs E E⁵ considerable force is exerted to move forward the frame B' and barrel B, while the breech-block is held back by the hooked lever F. The barrel is thus forcibly drawn from the empty cartridge-shell, which is held back by the extractor G. As soon as the barrel is 90 clear of the cartridge-shell the latter drops 95 out of the gun through apertures provided for the purpose in the frames A B', and the cartridge in the chamber A⁷ is pushed down by the springs A⁸ into position to be thrust into the barrel. When the frame B² has terminated or nearly terminated its forward movement, the shoulder or projection D⁶ on the sliding bar D⁴ strikes the lever F and disengages the same from the pivoted bar C'. The spring D then reacts and effects the forward or return movement of the breech-block. When the breech-block has thrust the cartridge into the barrel and closed the breech, the projection C⁵ on the said block strikes the sear I and disengages it from the hammer. 100 If the sear I' is held by the trigger-rod I⁴ out of engagement with the hammer, the hammer when released from the sear I, as above described, will immediately act upon the firing-pin and the gun will continue firing so 105 long as it is supplied with ammunition. When a number of barrels are associated, however, so that the discharge and recoil of one effects the discharge of another, the action will be understood by referring to 110 Fig. 4, in which the parts are shown in the positions which they occupy when the sear I' of the first barrel has been released by the corresponding cam I⁸, and the said barrel has been thus fired and is about to recoil 115 with the breech-block. In the recoil a projection B²⁶ on the barrel strikes the lever v' and turns the same upon or about its pivot v², thereby moving the said lever and the pawl v into the position indicated by dotted lines in 120 Fig. 4, so that the said pawl is caused by its spring to engage with the tooth I⁹. In the forward or return movement of the barrel the projection B²⁵ strikes the said lever v' and

through the medium of the said lever and the pawl *v* partially rotates the trigger-rod *I*⁴, thereby moving the cam *I*⁸ away from the sear *I'* and permitting the said sear to engage 5 with the hammer, the said hammer having been cocked by the breech-block in its recoil, as hereinbefore described. By the said partial rotation of the trigger-rod the cam *I*⁸ of the next succeeding or second barrel is caused 10 to disengage the corresponding sear *I'* from the hammer, so that the second barrel is fired. The third barrel will be fired in like manner by means of the projection *B*²⁵ on the second barrel, the cams *I*⁸ being so arranged upon 15 the trigger-rod that in each partial rotation of the said rod one or other of the sears *I'* will be disengaged from the corresponding hammer, and in each complete rotation of the said rod all of the barrels will be fired in succession. The sear *I*⁷ is designed to be disengaged from the hammer of the first barrel or 20 moved into engagement therewith by hand for the purpose of starting and stopping the firing of the gun. By disengaging the sear *I*⁷ and continuously rotating the trigger-rod *I*⁴ by means of a crank-handle *I*¹⁰ the barrels may be discharged in rapid succession by hand; or, if desired, one or more shots may be fired by partially rotating the said rod by 25 hand. This principle of construction and operation may obviously be applied to many other forms of gun than that specifically described herein in illustration of the invention.

What I claim is—

35 1. The combination, with two or more automatic guns, each consisting of a barrel and a breech mechanism therefor adapted to be

40 moved relatively to each other by the force of a discharge in said barrel, and a hammer and sears forming a part of each breech mechanism, of a trigger-rod mounted transversely to the barrels and adapted to release all the sears or firing mechanisms successively, and pawls intermediate to the trigger-rod and the moving parts of each gun, whereby the discharge of one gun turns said rod to fire another, as set forth.

2. The combination, with two or more sliding barrel and breech mechanisms, each constituting an automatic gun and mounted in a 45 common frame or support, of a trigger-rod mounted transversely to the same and adapted when turned to discharge the guns in succession, ratchets on said trigger-rod, and pawls between the same and each barrel and 50 adapted to be operated to turn the trigger-rod by the recoil of the barrels, as set forth.

3. The combination, with two or more sliding barrels and breech mechanisms, each constituting an automatic gun and mounted in a 55 common frame or support, of a trigger-rod mounted transversely to the same and provided with cams adapted to engage successively with the sears of the several guns when the trigger-rod is rotated, ratchets carried by 60 the trigger-rod, and pawls engaging therewith and extending into the path of the sliding barrels or projections thereon, as set forth.

In testimony whereof I have hereunto set my hand this 22d day of May, 1890.

HIRAM STEVENS MAXIM.
